UNITED STATES PATENT OFFICE.

EDWARD B. ALLEN, OF ELIZABETH, NEW JERSEY, ASSIGNOR TO THE SINGER MANUFACTURING COMPANY, A CORPORATION OF NEW JERSEY.

THREAD-CONTROLLING DEVICE FOR SEWING-MACHINES.

SPECIFICATION forming part of Letters Patent No. 784,291, dated March 7, 1905.

Application filed July 20, 1904. Serial No. 217,300.

To all whom it may concern:

Be it known that I, EDWARD B. ALLEN, a citizen of the United States, residing at Elizabeth, in the county of Union and State of New Jersey, have invented certain new and useful Improvements in Thread-Controlling Devices for Sewing-Machines, of which the following is a specification, reference being had therein to the accompanying drawings.

- 10 This invention relates to a specific embodiment of the improvement forming the subject of the United States Patent No. 757,171, granted to me April 12, 1904; and it has for its primary object the provision of means for handling the upper and lower threads of the machine, whereby the position of the interlock may be varied in respect of the needle-punctures in the material while retaining more nearly normal relative tensions upon the upper and lower threads throughout the cycle of the machine. Heretofore in machines of this general character in order to form the interlock upon the upper side of the material it has been customary to place a strong tension upon the upper thread and a very light tension upon the lower thread, which has subjected the upper thread to a liability of breakage by excessive strain thereon in the stitch-setting operation and has resulted in the formation of loose stitches likely to be disarranged in subsequent laundering operations when applied to white goods. By approximating the normal thread-tension conditions of the ordinary straight-ahead stitching-machines, in which the tensions upon the upper and lower threads are substantially equal, much better results are obviously attained.

The present invention consists, primarily, in the combination, with stitch-forming mechanism comprising a thread-carrying needle and an under-thread-carrying loop-taker, of means independent of the upper-thread devices for supplying for each stitch the requisite amount of under thread while maintaining a uniform tension thereon, and means for varying the under-thread supply for the stitches of successive groups.

In its preferred embodiment as applied to

an oscillating shuttle-machine of the well-known "Singer" type the improvement comprises, in addition to the usual pull-off flange carried by the shuttle, an auxiliary pull-off member connected with the shuttle-driver, in respect of which it is longitudinally movable and provided with means for periodically shifting its longitudinal position for the initial stitch of successive groups of stitches, whereby its effective action upon the shuttle-thread is periodically varied. As adapted to the class of buttonhole-stitching machines forming the subject of my United States Patent No. 738,591, of September 8, 1903, the auxiliary shuttle-thread pull-off member is controlled in its action by the feed-interrupting device connected with the barring mechanism; but it is to be understood that it is equally adapted for embroidering, hemstitching, and other machines designed for the production of groups of stitches of different character in ornamental patterns and that the improvement is not, therefore, limited to any particular type of buttonhole or other stitching machines.

The invention will be understood by reference to the accompanying drawings, in which—

Figure 1 is a front elevation of a button-hole-machine similar to that shown in my United States Patent No. 757,171, with a portion of the standard and base broken away to expose the parts within the same; Fig. 2, a bottom plan, and Fig. 3 a front elevation, of the same with the face-plate removed. Fig. 4 is a plan view, upon a larger scale, of the forward portion of the bracket-arm with the cover-plate of the barring mechanism removed. Fig. 5 is an edge view, and Fig. 6 a side view, of the feed-actuating eccentric-rod and accessories. Fig. 7 is a front view of the shuttle-driver, auxiliary pull-off, and its actuating devices; and Figs. 8 and 9 are plan views of the same, showing the pull-off in its extreme longitudinal positions; and Fig. 10 is a side elevation of the shuttle, its driver, and pull-off, showing the action of the latter upon the shuttle-thread.

The machine is constructed with the usual

work-plate 2 and overhanging arm 3, in which is journaled the driving-shaft 4, having at its forward end the crank 5, connected by pitman 6 with the vertically-reciprocating and laterally-vibrating needle-bar 7, having the needle 8 and carried by the swinging frame 9, the horizontal or lateral movements being communicated to the needle-bar frame by a cam-wheel 10, rotating once for each two rotations of the main shaft 4. The cam-wheel 10 has a cam-groove 11, entered by a pin or stud 12 on an arm of a lever or rocker 13 with its fulcrum or center of motion at 14 and connected through the bar 15, slotted swinging arm 16, and link 17 with an arm 18 of the needle-bar frame. The lever or rocker 13 is provided with a pin 19 and a keyhole-slot 20, disposed at different distances from its center of motion 14 and adapted to alternately engage the lateral notch 21 and depending roller-stud 22, respectively, of the bar 15. The pin 19 is normally embraced by the notch 21 under the action of the spring 15^x upon the bar 15 to cause the rocker 13 to impart to the needle-bar its shorter lateral movements for the side stitches of the buttonhole; but the bar 15 is periodically shifted in opposition to said spring to enable its roller-stud 22, normally embraced by the clearance-space afforded by the enlargement of the slot 20, to enter the contracted portion of the latter under the action of the spring-actuated pawl-lever 23 upon the stud 24, carried by the bar 15, such pawl deriving its reciprocations transversely of the arm by means of the snail-cam 25, (dotted in outline in Fig. 1,) acting upon the bent lever 23^x in opposition to the retracting-spring 26, which latter is of sufficient strength to overcome the tension of the spring 15^x. The pawl-lever 23 is pressed laterally, so as to snap over the stud 24 when in its extreme inner position by means of a spring 27 acting upon the tail of the same.

The pawl-lever 23 is shifted laterally in opposition to its spring 27 to release the stud 24 and permit the bar 15 to return to engagement with the pin 19 under the action of its spring 15^x by means of a bent lever 28, carried by the cover-plate of the barring mechanism, (shown in dotted lines in Fig. 4,) of which one arm lies in the path of movement of an adjustable stud 29, carried by a ratchet-wheel 30, while the other arm is adapted to engage a finger 31 of the pawl 23. As described in my Patent No. 757,171, a peripheral shoulder of the ratchet-wheel 30 rests normally in contact with an adjustable stoppin 32 under the action of a suitable retracting-spring; but while the bar 15 is in barring position the actuating-pawl 33, carried by the rocker 13, and the detent-pawl 34 remain in operative engagement with the ratchet-wheel and the former communicates to the same an intermittent rotary movement until the engagement of the stud 29 with the release-lever

28, when in its return to initial position under the action of the spring 15^x the bar 15 engages the tail of the actuating-pawl 33 and throws the latter out of operative engagement with the ratchet-wheel 30, while the detent-pawl 34 is simultaneously shifted into and thereafter maintained in its inoperative position by engagement with the pawl 33 in the latter's retracted position.

As shown and described in my said Patent No. 738,591, the main shaft 4 carries an eccentric 35, embraced by the strap of an eccentric-rod 36, having a shank provided with a lateral notch 37, loosely fitted to a socket in the pitman-rod 38, connected through the two-armed rocker 39 and pitman 40 with the lever 41 of a clutch device 42, engaging the feed-wheel 43 upon the shaft 44, carrying the snail-cam 25. To the pitman-rod 38 is pivoted at 45 a latch-lever 46, formed with a tooth 47, adapted to enter the notch 37 of the eccentric-rod 36 and having its upper end extended into the path of lateral movement of the rear end of the rod 15, by which it is shifted in opposition to the spring 48 to withdraw the tooth 47 from its notch 37, so as to permit the eccentric-rod 36 to reciprocate idly in its socket in the pitman-rod 38 to interrupt the normal actuation of the feed-cam while the bar 15 is in barring position, but to permit the restoration of the tooth 47 to engagement with the notch 37 and consequent resumption of feeding movements of the feed-cam when the bar 15 is restored to side-stitching position.

In the stitching of "purl-stitch" buttonholes by lock-stitch mechanism it is necessary that sufficient under thread be drawn up through the material for each stitch by the needle-thread to form the purl upon the upper face of the material and preferably intermediate the inner and outer needle-punctures. As has already been stated, this has heretofore been accomplished by employing a very loose tension upon the lower thread and a very strong tension upon the upper thread in order that the latter may supplement the normal action of the lower-thread pull-off in supplying the necessary lower thread for the stitch, the lower-thread pull-off having been heretofore necessarily limited in its action to the maximum amount of thread necessary for stitches requiring a minimum under-thread supply or barring-strokes. Such condition has been obviated by the present improvement in the provision of a variable under-thread pull-off, herein shown as auxiliary to the usual pull-off flange upon the shuttle, although evidently adapted to perform the desired function solely in each of its operative positions. By the adaptation of the shuttle-thread pull-off to measure off the exact amount of shuttle-thread for each side stitch and barring-stitch it is evident that the relative quantities of needle and shuttle threads will be thereby determined in the same manner as by measur-

ing off fixed amounts of the needle-thread, as described in my previous patent, No. 757,171, the action of the take-up 75 upon the needle-thread being in either case to set the stitch by drawing up against each other the requisite lengths of needle and shuttle threads.

In its present embodiment the shuttle 50 is mounted in the race 49 and is formed with the beak 51 and the usual pull-off flange 52. The shuttle-driver 53 is mounted upon the forward end of the oscillating shaft 54 and is provided with the usual arms engaging the throat and heel of the shuttle for communicating to the latter its oscillating movements. Upon the shuttle-driver shaft 54 is mounted the carrier for the pull-off, comprising a loose sleeve 55, provided with a forwardly-projecting arm 56, fitted to a guide-slot in the arm of the shuttle-driver and provided at its outer end with the circumferentially-extending pull-off finger 57, detachably secured thereon by means of the screws 58. The operative face of this pull-off finger is shown herein shaped to afford the final deflection for the lower thread α , intermediate the bobbin-case 70 and the under side of the work, as illustrated in Fig. 10, the initial pull-off action being effected by the ordinary pull-off flange 52, shown herein as formed integral with the shuttle. The bobbin-case 70 (illustrated only in dotted lines in Fig. 10) is of the well-known Singer type and is provided with the usual tension-spring 71, between which and the outer wall of the bobbin-case the lower thread is led to the under side of the work. It is obvious that the pull-off member 57 may be made of such form as to draw off from the bobbin the full supply of under thread, when the corresponding member of the shuttle may be dispensed with.

As represented in Fig. 3, the forward end or point of the pull-off finger 57 is so disposed as to overlap the adjacent portion of the pull-off flange 52 of the shuttle, and being turned inward slightly, as indicated in Figs. 8 and 9, is so disposed as to avoid catching the shuttle-thread as it is led from the bobbin-case 70. It will thus be observed that as represented herein the pull-off finger 57 forms practically a continuation of the pull-off flange 52 of the shuttle, of which it thus constitutes an adjustable portion, and that in the return of the shuttle to loop-taking position after the formation of a stitch the ordinary and well-known action of its pull-off flange in deflecting that portion of the shuttle-thread intermediate the bobbin-case and the work is increased by the supplemental action of the pull-off finger 57, which is similar thereto, but obviously differs in extent, depending upon its longitudinal position relative to the shuttle.

The sleeve 55 is provided with an annular groove 59, entered by a lateral arm 60, carried by a reciprocating rod 61, mounted in the forward shuttle-shaft bearing 62 and connected with a second reciprocating shift-rod 63,

mounted in a fixed bracket 64, between which and a collar 65 upon said rod is interposed a spring 66 for maintaining such rods and the pull-off member 57 in inner or retracted position. The lower end of the latch-lever 46 is provided with a cam-piece 67, secured vertically adjustable thereon by means of the screw 68 entering the longitudinal slot 69 therein. The upper portion of this cam-piece is beveled upon the end and one side for engagement with the rearward extremity of the sliding rod 63, as indicated more particularly in Figs. 8 and 9.

When the latch-lever 46 is in initial locking position, as represented in full lines in Figs. 6 and 9 and in dotted lines in Fig. 7, the cam-piece 68 is in engagement with the rod 63, and thus maintains the pull-off member 57 in its outer position for producing a maximum under-thread supply for each stitch, as indicated in Fig. 10, while the shifting of the latch-lever 46 under the action of the bar 15 for the barring operation, as indicated in full lines in Figs. 7 and 8, effects the movement of the operative end of the cam-piece 67 aside out of engagement with the rod 63, which latter is enabled under the action of its spring 66 to withdraw the pull-off member 57 into its inner position, and thereby reduce the effective action of the same upon the under thread and to correspondingly reduce the amount of shuttle-thread drawn into the stitch, whereby the position of the interlock is changed for the barring-strokes. When the bar 15 returns to side-stitching position, and consequently releases the upper end of the latch-lever 46, the latter resumes its operative relation with the eccentric-rod 36 and the cam-piece 67 is again thrust into operative engagement with the end of the rod 63 to extend the pull-off member 57 into its outer position.

In cases wherein it is desired to produce so-called "whip-stitch" buttonholes, or those in which the interlock of the upper and lower threads is uniformly intermediate the upper and lower faces of the material, the cam-piece 67 may be shifted by loosening the fastening-screw 68 downwardly into inoperative position, in which its operative portion is entirely below the rod 63, whereby the latter is permitted to remain throughout the cycle of the machine in retracted position and the pull-off member 57 to consequently act uniformly in the stitching of the entire buttonhole.

As herein shown and described, the cam-piece 67 is formed with only a single step, inasmuch as the barring mechanism with which it is connected provides for only a single shifting movement between extreme positions; but it is evident that the number and size of the steps with which said cam-piece is provided, and hence the number and extent of variations in the pull-off actions, will be dependent upon the character of the pattern-controlling mechanism (herein represented as barring mechanism) employed in conjunction with the

stitch-forming devices, and the improvement is thus well adapted for machines of other types than those constructed for stitching buttonholes.

- 5 As regards its automatic feature the present improvement differs essentially from others in effecting the change in the supply of under thread intermediate the production of two consecutive stitches—viz., as hereinbefore described, the final stitch of one group and the initial stitch of the succeeding group—whereby the relative character of such stitches, together with the other stitch or stitches of the respective groups, is varied. As 15 regards this part of the present invention it is immaterial with what frequency the changes of position of the pull-off device relative to the loop-taker is effected, this being determined by the character of the stitching for 20 which the machine is designed.

The pull-off mechanism herein shown and described is adapted for adjustment to vary the action upon the shuttle-thread by the provision of a loose collar 72 upon the rod 63, formed with an arm 73, forked at its outer end to embrace an angular neck upon the rod 61, such collar being adjustably secured upon its rod by means of the set-screw 74. The pull-off member 57 may therefore be set to pull 25 off, initially, different lengths of thread, although its motion under the action of the cam-piece 67 is uniform for all adjustments in producing the groups of stitches of different characters, as before described.

35 From the foregoing description it will be seen that the under-thread pull-off or regulating device is controlled directly by means of the feed-interrupting device, which is actuated from the barring mechanism. The means for 40 varying the position of concatenation of the stitches in respect of the needle-punctures may therefore be properly said to be controlled by the feed-interrupter or by the mechanism serving to increase the lateral throw of 45 the needle for producing the barring-strokes, one of said actuating parts only being necessary to produce the automatic action upon the shuttle-thread described.

It is evident that the present improvement 50 is susceptible of wide modification from the embodiment herein shown and described, its essential feature being primarily the control of the character of the stitches composing successive groups by manipulation of the lower 55 thread, while the action of the upper-thread-handling devices remains uniform for all stitches produced throughout the cycle of the machine.

Having thus set forth the nature of my invention, what I claim herein is—

- 60 1. In a sewing-machine, the combination with stitch-forming devices comprising a reciprocating thread-carrying needle and an under-thread loop-taker coöperating therewith, of a needle-thread take-up, and automatic-

ally-controlled means coöperating with said loop-taker for supplying equal amounts of under thread for each of two or more consecutive stitches constituting a group, and for varying the amount of under thread supplied 70 for the initial stitch of each group in respect of those of the preceding group.

2. In a sewing-machine, the combination with stitch-forming mechanism comprising a thread-carrying needle and an under-thread 75 loop-taker, of a pull-off acting uniformly upon the under thread in the formation of a succession of stitches, and means for automatically controlling said pull-off to vary its effect upon the under thread in the production of 80 the stitches of different successions or groups.

3. In a sewing-machine, the combination with stitch-forming mechanism comprising a thread-carrying needle and an under-thread 85 loop-taker, of a pull-off acting uniformly upon the under thread in conjunction with the said loop-taker in the formation of each stitch of a group of stitches, and a device acting periodically upon the pull-off in the formation of the initial stitch of each group to vary the 90 effect of said pull-off in its action upon the under thread for the stitches of said group.

4. In a sewing-machine, the combination with stitch-forming devices comprising a reciprocating thread-carrying needle and an 95 under-thread loop-taker coöperating therewith, of a device acting directly upon the under thread for supplying equal quantities of the same for the stitches of each group or succession, and means for automatically controlling said device for varying the under-thread supply for the stitches of successive groups.

5. In a sewing-machine, the combination with upper-thread mechanism acting uniformly 105 upon its thread for each stitch and under-thread mechanism adapted to act upon the under thread uniformly for the stitches of each group or succession of stitches, of automatically-controlled means acting upon the 110 under thread whereby the thread-supply for the stitches of each group or succession is varied from that of the stitches of the preceding group or succession.

6. In a sewing-machine, the combination 115 with a thread-carrying needle and a uniformly-acting take-up and tension for the needle-thread, and a loop-taker and lower-thread holder with uniformly-acting lower-thread tension, of a device independent of the upper-thread take-up and tension for controlling the under-thread supply to automatically vary the same at the end of each succession or group of stitches.

7. In a sewing-machine, the combination 125 with stitch-forming mechanism comprising a needle and complementary under-thread stitch-forming devices, of a tension device acting uniformly upon the thread in all the stitch-setting operations, means for setting the 130

- stitches, a device acting upon the under thread whereby the position of concatenation of the upper and lower threads in respect of the needle-punctures may be varied, and automatic means for controlling the operation of said device for changing the position of concatenation of the stitches of succeeding groups at predetermined times.
8. In a sewing-machine, the combination with the work-plate and stitch-forming mechanism comprising a thread-carrying needle and an under-thread loop-taker, disposed respectively above and below said work-plate, of a device operating below the work-plate for regulating the supply of thread for each stitch, and means for controlling said device to automatically vary the relative lengths of thread for the stitches of successive groups.
9. In a sewing-machine, the combination with stitch-forming mechanism comprising a thread-carrying needle and an under-thread loop-taker, means for setting the stitches, and regulating means acting directly upon the under thread for determining the relative lengths of upper and under thread supplied for each stitch, of a device acting automatically upon said regulating means to vary the relative thread-supply for successive stitches and thereby vary the position of concatenation of the threads in respect of the needle-punctures.
10. In a sewing-machine, the combination with stitch-forming mechanism comprising a thread-carrying needle and an under-thread loop-taker, of an under-thread pull-off device movable with said loop-taker, and means for automatically shifting the same relatively to said loop-taker to vary its action upon the under thread.
11. In a sewing-machine, the combination with stitch-forming mechanism comprising a thread-carrying needle and an under-thread loop-taker, of an under-thread pull-off device movable with said loop-taker, and means for automatically shifting the same relatively to said loop-taker after the operation of the latter in the formation of each group or succession of stitches.
12. In a sewing-machine, the combination with a vertically-reciprocating thread-carrying needle and a shuttle provided with a suitable thread-case, of a shuttle-driver, a circularly-moving shaft upon which the shuttle-driver is mounted, a sleeve mounted upon and circularly movable with said shaft, a pull-off finger carried by said sleeve, means for shifting said sleeve upon its shaft, and means for actuating said shaft.
13. In a sewing-machine, the combination with a vertically-reciprocating thread-carrying needle and a shuttle provided with a suitable thread-case, of a shuttle-driver, a circularly-moving shaft upon which the shuttle-driver is mounted, a sleeve mounted upon and circularly movable with said shaft but longitudinally movable thereon, a pull-off finger carried by said sleeve, automatically-acting means for shifting said sleeve upon its shaft at the end of each group or succession of stitches, and means for actuating said shaft.
14. In a sewing-machine, the combination with stitch-forming mechanism comprising a vertically-reciprocating and laterally-vibrating needle and an under-thread loop-taker, of means for automatically changing the extent of vibration of said needle for successive stitches, a regulating device for determining the quantity of under-thread supply for each stitch, and a connection between said means and the under-thread-supply-regulating device for effecting a change in the under-thread supply correspondingly with that of the lateral vibrations of the needle.
15. In a buttonhole stitching and barring machine, the combination with a vertically-reciprocating needle and an under-thread loop-taker, of controlling means acting upon the lower thread for regulating the under-thread supply for each stitch, barring mechanism, and means connected with the barring mechanism for operating said controlling means to vary the under-thread supply.
16. In a sewing-machine comprising upper and under thread stitch forming and feeding mechanisms, and a feed-interrupter for temporarily suspending the feed of the work at the end of each group or succession of stitches of predetermined number, the combination with controlling means for regulating the supply of under thread for each stitch, of means connected with and actuated by said feed-interrupter for operating said controlling means to vary the supply of under thread.
17. In a sewing-machine comprising upper and under thread stitch forming and feeding mechanisms, and a feed-interrupter comprising a two-part connecting-rod and a laterally-movable latch-lever therefor periodically actuated for temporarily suspending the feed of the work, the combination with a pull-off operating in conjunction with said under-thread mechanism for determining the quantity of lower thread supplied for each stitch, of a shift-rod connected with said pull-off, and a cam-piece carried by said feed-interrupting latch-lever and engaging said shift-rod to periodically shift said pull-off.
18. In a sewing-machine, the combination with stitch-forming mechanism comprising a thread-carrying needle and an under-thread loop-taker, of an under-thread pull-off device movable with said loop-taker, and automatically-acting means for shifting the same in respect of said loop-taker for the production of different stitches of a succession of stitches to vary its action upon the under thread.
19. In a sewing-machine, the combination with stitch-forming mechanism comprising a thread-carrying needle and an under-thread loop-taker, of an under-thread pull-off device circularly movable concentrically with and

shiftable transversely of the path of movement of said loop-taker, and means normally stationary in respect of the loop-taker for shifting said pull-off to vary its action upon the under thread.

- 5 20. In a sewing-machine, the combination with stitch-forming mechanism comprising a thread-carrying needle and a circularly-moving under-thread loop-taker, of a pull-off device with means for actuating it to control the under-thread supply for each stitch, and means 10 acting automatically to shift the position of said pull-off in respect of the loop-taker after the production of the first of two consecutive 15 stitches for changing its action upon the under thread and thus by affecting the under-thread supply changing the relative characters of said stitches.
- 20 21. In a sewing-machine, the combination with stitch-forming mechanism comprising a thread-carrying needle and a circularly-moving under-thread loop-taker, of a pull-off device with means for actuating it to control the under-thread supply for each stitch, and means 25 acting automatically to maintain said pull-off device in one position in respect of the loop-

taker for the production of two separate groups of stitches and to shift it into another position in respect of said loop-taker for the production of an intervening stitch or stitches 30 whereby a succession of stitches composed of groups differing in character is formed.

22. In a sewing-machine, the combination with stitch-forming devices comprising a reciprocating thread-carrying needle, a shuttle 35 and a circularly-moving driver therefor, of an under-thread pull-off device acting in conjunction with said shuttle to measure off the under-thread supply for each stitch, a carrier therefor mounted upon said driver and fitted to 40 a longitudinal slideway in the same, and means for shifting said pull-off device transversely of the path of movement of said loop-taker to vary its action upon the under thread.

In testimony whereof I have signed my name 45 to this specification in the presence of two subscribing witnesses.

EDWARD B. ALLEN.
